[57] **CLAIM**

The ornamental design for a medical instrument handle, as shown and described.

DESCRIPTION

FIG. 1 is a perspective view of a medical instrument handle showing our new design, the broken line showing is for illustrative purposes only and forms no part of the claimed design;

FIG. 2 is a bottom plan view thereof;

FIG. 3 is a rear elevational view thereof;

FIG. 4 is a right side elevational view thereof;

FIG. 5 is a left side elevational view thereof;

FIG. 6 is a left side elevational view thereof;

FIG. 7 is a front elevational view thereof;

FIG. 8 is a perspective view of a second embodiment of a medical instrument handle showing our new design, the broken line showing is for illustrative purposes only and forms no part of the claimed design;

FIG. 9 is a bottom plan view thereof;

FIG. 10 is a rear elevational view thereof;

FIG. 11 is a right side elevational view thereof;

FIG. 12 is a top plan view thereof;

FIG. 13 is a left side elevational view thereof; and,

FIG. 14 is a front elevational view thereof.
